UNITED STATES PATENT OFFICE.

FRANK H. FARMER, OF CLEVELAND, OHIO, ASSIGNOR TO THE WHITE MOTOR COMPANY,
OF CLEVELAND, OHIO, A CORPORATION OF OHIO.

MOTOR-VEHICLE.

1,300,151.

Specification of Letters Patent. Patented Apr. 8, 1919.

Application filed September 4, 1917. Serial No. 139,471.

To all whom it may concern:

Be it known that I, FRANK H. FARMER, a citizen of the United States, residing at Cleveland, in the county of Cuyahoga and State of Ohio, have invented a certain new and useful Improvement in Motor-Vehicles, of which the following is a full, clear, and exact description.

This invention relates to means for suspending the motor upon the chassis frame of a motor vehicle; and is a novel form of what has come to be known as "a three point suspension".

The object is to so suspend the motor upon the vehicle frame that when the frame is distorted, as it goes over uneven road surfaces, the motor and frame may move relatively to an extent such as will prevent any breakage.

The invention consists in the construction and combination of parts shown in the drawing and hereinafter described and pointed out in the appended claims.

In the drawing, Figure 1 is a plan view of the front end of a motor vehicle frame with the motor suspended thereon according to this invention. Fig. 2 is a side of the same parts. In these two figures the motor and its frame are wholly or partly concealed by the hood. Fig. 3 is a vertical section of rear elevation of the parts of the chassis frame and motor frame which include this invention. Fig. 4 is a plan view of the two sides of the chassis frame and the brackets upon which rear end of the engine frame is supported. Fig. 5 is a sectional front elevation of the chassis frame and the bearings for the front end of the motor frame. Fig. 6 is a vertical longitudinal section, through the means by which the front end of the motor frame is supported.

Referring to the parts by reference characters, 10 and 12 represent respectively the two side members of the chassis frame of a motor vehicle; and 13 represents a transverse frame member located adjacent the front end of the chassis frame.

20 represents the engine frame, which is of conventional form and may be made, as is common, of aluminum. This frame has at its front end a forwardly projecting horizontal, tubular trunnion 21, which is rotatively mounted in the bearing 17 carried by a bracket 18 that is fixed to the transverse frame member 13. At its rear end and on each side thereof the motor frame is pro-

vided with a foot 22, which may be of and is shown as of common form.

Fixed respectively to the two side frame members 10 and 12, and projecting inwardly therefrom are the two brackets 30, on the horizontal part 31 of which the motor feet are supported. Each bracket, in the preferred form as shown, consists of the bent plates 33 and 34. The former is riveted to the vertical web *a* of the associated frame member, while the latter is riveted to the inwardly projecting flange *b* on the lower edge of said frame member. These two bracket plates converge, and the horizontal part 33^a of one rests upon and is riveted to the horizontal part 34^a of the other, thereby making a double thick horizontal shelf 31. In one of these bracket shelves 31 is a transversely elongated slot 31^b; while in the other shelf is a longitudinally elongated slot 31^c.

Each foot of the engine frame is secured to and upon a chair 40. Each chair is an angle iron which contacts with the lower and outer surface of the foot. It is formed with a downwardly projecting stud 41 which, when the chair rests upon the associated bracket, goes through one of the holes 31^b, 31^c. A spring 43 surrounds the projecting lower end of said stud, and is put under tension by a nut 45 which screws onto said stud, the spring lying between two washers 46, 47 upon said stud.

From the foregoing, it is evident that the feet at the rear end of the engine frame are yieldingly held down on the supporting brackets, but that each foot is permitted a short movement upward relative thereto and, of course, to the associated frame member. Likewise the engine frame and one of the side members 12 of the chassis frame may move laterally a short distance relative to the other member 10, to which is secured the bracket having the transversely elongated slot. So also may the engine frame and the chassis frame member 10 move longitudinally relative to the frame member 12 which carries the bracket with the longitudinal elongated slot.

The above described means for securing the engine to the chassis frame is such that however the chassis frame may be distorted in use, and regardless of the direction and kind of distortion, there will be no breakage of the engine feet or the means by which they are connected with the chassis frame.

Having described my invention, I claim:

1. In a motor vehicle, the combination with the chassis frame, and inwardly extended brackets secured respectively to the two side members of the chassis frame, an engine frame having a foot at each side and adjacent its rear end, said brackets being disposed respectively beneath the feet of the engine frame, and means which yieldingly draw the feet of the engine frame down upon said brackets, but which permits one foot to move laterally relative to the adjacent side member of the chassis frame and permits the other foot to move longitudinally relative to the adjacent side member of the chassis frame.
2. In a motor vehicle, the combination of the chassis frame, an engine frame having a foot on each side adjacent the rear end, means for suspending the front end of the engine frame from the chassis frame on a longitudinally extended, centrally placed, horizontal pivot, a chair which is fitted and fixed to each foot and is provided with a downwardly extended stud, inwardly extended brackets fixed respectively to the two side members of the chassis frame and project respectively under and into engagement with said chairs, one of said brackets having a transversely elongated slot through which the stud on the associated chair projects and the other bracket having a longitudinally elongated slot through which the stud on the associated chair projects, and means engaging said studs to hold said chair down upon said brackets.
3. In a motor vehicle, the combination of the chassis frame, an engine frame having a foot on each side adjacent the rear end, means for suspending the front end of said engine frame from the chassis frame on a longitudinally extended centrally placed horizontal pivot, a chair fitted and fixed to each foot and provided with a downwardly extended stud, inwardly extended brackets fixed respectively to the two side members of the chassis frame and projecting respectively under and into engagement with said chairs, one of said brackets having a transversely elongated slot through which the stud on the associated chair projects, and the other bracket having a longitudinally elongated slot through which the stud on the associated chair projects, a nut which screws onto the lower end of each stud, and a coil spring which surround the projecting lower end of each stud and is compressed between the nut and bracket.

In testimony whereof, I hereunto affix my signature in the presence of two witnesses.

FRANK H. FARMER.
